UNITED STATES PATENT OFFICE.

WILLIAM P. BUTLER, OF CHICAGO, ILLINOIS.

VAPOR-BURNER.

SPECIFICATION forming part of Letters Patent No. 362,929, dated May 17, 1887.

Application filed May 13, 1886. Serial No. 202,074. (No model.)

To all whom it may concern:

Be it known that I, WILLIAM P. BUTLER, a citizen of the United States, residing at Chicago, in the county of Cook and State of Illinois, have invented new and useful Improvements in Vapor-Burners, of which the following is a specification.

My invention relates to vapor-burners, and the objects are to provide novel means for imparting heat to the pipe by which the hydro-carbon is conveyed to the jet-burner, to provide novel means for supporting the burner, whereby it can be quickly detached to permit its being cleaned, which is very desirable, owing to the fact that small insects are drawn into it from below, and to provide novel means for determining the proper position of the detachable burner when replaced, whereby its slotted tip will be so positioned as to cause the flame to issue laterally on the upper solid end of the gas conducting and heating pipe.

To such ends the invention consists in the several novel features of construction and combinations of parts hereinafter set forth, and definitely pointed out in the claims annexed to this specification.

In the accompanying drawings, Figure 1 is a side elevation, partly in section, illustrating my invention. Fig. 2 is a plan view; Fig. 3, a broken detail perspective view, showing the disk-rest at the lower end of the gas generating pipe; and Fig. 4, a perspective view of the burner detached.

In the said drawings, the reference-numeral 1 denotes that portion of the supply-pipe which is next to the burner. At its end it is provided with a vertical pipe, 2, at right angles therewith, which drops below the supply-pipe and is supported by a bracket, 3. At the lower end of the pipe 2 is formed a disk-rest, 3^a, for the burner, beneath which is a short branch of tubing, 4, formed by chambering the disk-rest, which conveys the gas to a point beneath the burner, to which it is delivered through a minute opening, 5, which opens into the open end of the burner. This opening is closed by a needle, 6, operated by a screw, 7.

The burner 8 is of a cylindrical form, and on the disk-rest for the burner the open end rests upon a rib, 8^a, the position of the burner on the disk-rest being determined by notches

9 in the lower end of the burner, which engage with the rib. The burner is held upright by an annulus, 10, projecting laterally from the vertical pipe 2, and when in position the lower end of the slot 11 is brought adjacent to the upper extremity of the said pipe, so that the flame from the burner-tip is directed laterally upon such upper end of the pipe. The burner is readily detached by lifting it from the annulus or ring 10, which is desirable for the purpose of cleaning it, especially from small insects that are drawn into it from below. The notches 9 in the lower end of the burner serve as a means for determining the proper position of the slotted tip of the burner with reference to the upper solid stem-like end of the pipe 2, when the burner is replaced in position, this being effected, as stated, by said notches engaging the rib 8^a on the disk-rest.

In the wall of the burner, about midway of its length, is found an aperture, 12, through which a sub-jet of gas may be projected against the vertical pipe 2 and beneath the hood 13, which partly surrounds a diminished portion 75 of the supply-tube. This sub-jet serves to heat the tube sufficiently to volatilize the hydrocarbon before it enters the mixing-chamber in the lower end of the burner.

When the escaping gas is ignited, the flame 80 will impinge upon the upper extremity of the tube 2, which, at the points exposed is of solid metal. By this means additional heat is derived, which, in case the sub-jet should be extinguished, will impart sufficient heat to the 85 tube to maintain the volatilization of the hydrocarbon.

What I claim is—

1. In a vapor-burner, the combination of the gas generating tube 2, having a disk-rest, 3^a, 9c at its lower end, and provided above said disk-rest with a laterally-projecting ring, 10, with the burner detachably held within said ring and loosely supported by the disk-rest, substantially as described.

2. In a vapor-burner, the combination of the generating pipe 2, having a disk-rest, 3^a, at its lower end, and provided above said disk-rest with a laterally-projecting ring, 10, with a burner detachably held within said ring and 100 having a slit in its tip arranged at one side, adjacent to the solid upper end of the pipe, to

direct the flame laterally upon said upper end of the pipe, substantially as described.

3. In a vapor-burner, the combination of the gas-generating pipe 2, having a laterally-projecting ring, 10, and a disk-rest, 3^a, below the latter, having the rib 8^a of the burner detachably held within said ring, and having a notched lower end engaging said rib, substantially as and for the purposes described.

10 4. In a vapor-burner, the combination of the gas-generating pipe 2, having the laterally-projecting ring 10, and provided at its lower

end with a disk-rest, 3^a, having a rib, 8^a, with a burner detachably held within said ring, and having a sub-jet orifice, 12, and a notched 15 lower end engaging the rib, substantially as described.

In testimony whereof I affix my signature in presence of two witnesses.

WILLIAM P. BUTLER.
